TOOL FOR REMOVING AND REPLACING CONTAINER TOPS

William W. Woodbury, 1121 Stanyan St.,
San Francisco, Calif.

Filed Sept. 11, 1961, Ser. No. 66,685

Term of patent 14 years

(Cl. D44—29)

The drawing is a perspective view of a tool for removing and replacing container tops, showing my new design.

The bottom surface, not shown, is substantially planar and is unornamented.

I claim:

The ornamental design for a tool for removing and replacing container tops, as shown and described.
